UNITED STATES PATENT OFFICE

FRANK L. FURBUSH, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS

CONTINUOUS EXTRACTOR

Application filed December 14, 1926. Serial No. 154,823.

This invention relates to a device for extracting moisture from comminuted matters such as rubber fibre and the like.

The principal objects of the invention are to provide an improved means for driving the endless apron on which the material is carried through the squeeze rolls; to provide an improved form of apron which will pass around the drums at the ends of the device without binding and with less wear than has been the case heretofore; in combination with the links of the apron; to provide a convenient means for exerting pressure on the upper press rolls and relieving them of pressure readily, and to provide an auxiliary means which will drive the apron that will work positively at any time when the main driving means loses control of the apron.

Other objects and advantages of the invention will appear hereinafter.

Reference is to be had to the accompanying drawings in which

Fig. 1 is a side view of a duplex continuous extractor constructed in accordance with this invention;

Fig. 2 is a transverse sectional view on the line 2—2 of Fig. 1;

Fig. 3 is a sectional view on the line 3—3 of Fig. 2 showing the ratchet driving arrangement;

Fig. 4 is a sectional view on the line 4—4 of Fig. 2;

Fig. 5 is a plan of the apron and chain; and

Fig. 6 is a sectional view on the line 6—6 of Fig. 5.

This invention relates to a machine for extracting moisture from wet comminuted rubber or other fibrous material. These machines usually have an endless apron in which the several links are connected together by hinges which pass over octangular or similar drums at the ends. The swinging of the plates on their hinges as they pass over the drums is accompanied by considerable wear and in case of lack of exact registration the hinge parts are apt to be bent. The result is that they wear at the hinges first and the hinges limit the life of the machine. The collection of the liquid pressed out of the material

is also a matter of considerable trouble because it is apt to get into the joints and bearings of the machine, with obviously bad results. This invention is designed to avoid these difficulties largely and one of the principal features is the construction of the apron in such a manner that the apron itself will have no hinges and will depend upon the great flexibility of sprocket chains of certain constructions.

For the purpose of securing the above mentioned results I have shown in the drawings a duplex machine, although it is to be understood that a machine with a single pair of extracting rollers can be constructed on the same principle. On this machine I have provided the frame 10 with bearings for the studs of a pair of lower pressure rollers 11 spaced a distance apart and with a pair of slots 12 for the studs of a pair of upper rollers 13. These upper rollers 13 bear with their whole weight on the lower rollers. Levers 15, which are pivoted at 16, transmit pressure through bearings 14 to the upper rollers. The levers 15 are pressed upon by springs 17 adjustably mounted by hand nuts 18 on vertical rods 19. These rods have hooks 20 at the bottom engaging under end levers 21 pivoted at 22 and extending to the center of the machine where they receive pressure from rods 23 which carry weights 24 at the top. These weights can be adjusted by the usual practice of putting on or taking off the weighting discs. The rods are guided in the usual way.

I have shown a pair of these sets of rolls between which passes the endless apron formed of the links 25. Each these links consists of a plate which is provided with perforations. These plates are beveled on their opposite ends so that when two plates swing about an axis at their ends the edges will not interfere with each other as indicated in Fig. 4. Each plate is covered with a brass plate 26 which is turned over at its edges to fit the inclined edge of the iron plate and secured thereto. This brass plate is provided with very fine perforations while the perforations in the metal plate are coarse. The plates constituting the apron are entirely separate from each other and although they come into con-

tact, or nearly so, they are not secured directly together but each plate is secured to a sprocket chain 27 on each side. These sprocket chains may be made of any desired character and each link is provided with an ear 28 which is riveted or otherwise secured to the plates 25.

The apron is driven by a frictional contact with the rolls 11 and 13, two pairs of which are indicated here. I prefer this drive as it is an easy drive on the sprocket chains. However, in some cases the drive of the apron might be interrupted by various conditions that may result in this industry. For the purpose of keeping the chains going at such times and automatically restoring them to this friction drive when this is over, I provide an auxiliary drive. On the shaft of one of the rollers 11 is placed a sprocket wheel 29 and on a shaft 30 is placed another sprocket wheel and the latter is driven from the former by a sprocket chain 31. This sprocket wheel on the shaft 30 is larger than the driving sprocket wheel and consequently would drive the apron at less than its normal speed. It is connected with the apron by a pawl and ratchet device comprising spring ratchet pawls 33.

In the ordinary operation of the device this ratchets over without performing any function but if the apron is not driven by the rolls, the ratchet device will positively operate the apron at a lower speed. When the rolls are working normally again, they take up the apron and run it at full speed, thus rendering the ratchet device inactive.

The liquid extracted from the material by the press rolls drops down below, of course, and is received in the troughs 35 on both sides in the present case. They extend clear to the center so that they will receive all of the liquid drained out. At the bottom they are provided with depressions 36 which can drain out at one end by gravity or can be attached to a hose connection and pumped out. This affords a means for getting the water or other liquid out of the machine either continuously or intermittently.

The studs 30 of one driving drum for the apron are adjustable by screws 39 while the opposite stud is put in stationary position preferably, as only one adjustment is necessary. The driving of the apron is performed in the usual way by means of a driving shaft and gears as indicated in Fig. 2.

For the purpose of raising the weights 24 and the bearings 14 so as not to bear a weight on the rollers 13 when the machine is idle, the rods 23 are provided with sleeves 40 capable of sliding slightly thereon but adapted to engage the weights at the top. Each of these sleeves is connected by a link 41 to a lever 42 pivoted at 43. This lever has a link 44 pivotally connected to a hand lever 45 which itself is pivoted at 46. The normal

position is shown at the left in Fig. 2. When it is desired to raise the weights, in case the machine is idle, the handle 45 is depressed as shown at the right. This pulls down the link 44 and swings the lever 42 on its pivot so as to push up the lever 41 and therefore raise the weights on the rods 23. One of these is shown at each side of the machine.

This machine is more durable than the machines now on the market on account of the removal of the weak point in the apron. The sprocket chains for driving the aprons are not weakened in any way and do not present the same difficulty in the pivotal connections as the links heretofore used. The liquid is caught and drained off without so much danger of its reaching and rusting the bearings or chains.

Although I have illustrated and described only a single form of the invention I am aware of the fact that modifications can be made therein by any person skilled in the art without departing from the scope of the invention as expressed in the claims.

Therefore, I do not wish to be limited to all the details of construction herein shown and described, but what I do claim is:—

1. In an extracting machine, the combination with a pair of extracting rolls, of an apron passing between them, said apron being made up of plates free at their edges from each other and sprocket chains on each side connected with the several plates to complete the apron, whereby the passage of the apron between the rolls will drive it, means for driving one of the rolls, and positive means comprising a ratchet device for driving the apron at a lower speed whenever the press rolls do not drive it at a speed greater than said lower speed.

2. In an extractor, the combination with a pair of press rolls, means for driving the lower roll, and means for pressing the upper roll against the lower roll for the purpose of expressing water from rubber or fibrous material, of an endless apron passing between the press rolls and comprising a series of plates for carrying the material, a pair of chains connected with the opposite ends of said plates, said sprocket chains constituting the only means for connecting the plates, whereby the adjacent edges of the plates are free from each other, a drum at each end over which the apron passes, said apron being driven freely by the press rolls, a sprocket wheel on the shaft of the lower press roll, a larger sprocket wheel on the shaft of one of the drums, a sprocket chain connecting said sprocket wheels, and a ratchet mechanism between the larger sprocket wheel and the drum, whereby the sprocket wheel and ratchet arrangement will operate idly under normal conditions, but when the apron is not driven at a speed as high as that of the larger sprocket wheel, the latter through its ratchet

mechanism, will drive the drum and thereby the apron positively at lower than normal speed.

3. In an extractor, the combination with a pair of press rolls, of an endless apron passing between the press rolls, a drum at each end over which the apron passes, said apron being driven freely by the press rolls, a sprocket wheel on the shaft of the lower press roll, a larger sprocket wheel on the shaft of one of the drums, a sprocket chain connecting said sprocket wheels, and a ratchet mechanism between the larger sprocket wheel and the drum, whereby the sprocket wheel and ratchet arrangement will operate idly under normal conditions, but when the apron is not driven at a speed as high as that of the larger sprocket wheel, the latter, through its ratchet mechanism, will drive the drum and thereby the apron positively at lower than normal speed.

4. In an extractor, the combination with a pair of press rolls, one being mounted in fixed bearings, and means for positively driving it, the other press roll being mounted freely to move up and down and press on the lower roll, of means for applying weights to the upper press roll to cause it to bear with considerable pressure on the lower roll, said means involving a vertical rod, a weight thereon at the top, a sleeve on the rod adapted to be moved up to engage the weight, a link depending from said sleeve, a lever connected with the link below the sleeve and pivoted between its ends, a second link depending from the opposite end of the lever, and a hand lever pivoted beyond the second link and connected with it.

5. In an extractor, the combination with a pair of press rolls, of means for applying pressure to the upper press roll to cause it to bear with considerable pressure on the lower roll, said means involving a vertical rod, a weight thereon, a sleeve on the rod adapted to be moved up to engage the weight, a link connected with said sleeve, a lever connected with the link and pivoted between its ends, a second link connected with the opposite end of the lever, and a hand lever pivoted beyond the second link and connected with it, whereby, when the hand lever is depressed, the first-named lever will be raised at the end connected with the first-named link and will raise said sleeve to release the apparatus of the weight, said pivots being in such relation to each other that the two pivots at the two ends of the first-named link will be in alignment with the pivot of the first-named lever, whereby the parts will be retained in this position when pressure is removed from the hand lever.

In testimony whereof I have hereunto affixed my signature.

FRANK L. FURBUSH.
